CLAIM

The ornamental design for a single gang cable pass through plate, as shown and described.

DESCRIPTION

FIG. 1 is a front perspective view of the single gang cable pass through plate showing my new design;

FIG. 2 is a top plan view of the cable pass through plate of FIG. 1;

FIG. 3 is a bottom plan view of the cable pass through plate of FIG. 1;

FIG. 4 is a left side view of the cable pass through plate of FIG. 1 with the right side view being a mirror image of FIG. 4; and,

FIG. 5 is a left end view of the cable pass through plate of FIG. 1 with the right end view being a mirror image of FIG. 5.

1 Claim, 3 Drawing Sheets

FIG. 1
